ARCH FILE

Joseph A. Gibson, Kimball, Nebr.

Application October 26, 1939, Serial No. 301,379

5 Claims. (Cl. 129—11)

This invention relates to an arch lock binder and has for its principal object the provision of a neat, simple, and highly efficient device which can be quickly and easily opened to receive sheets and quickly and easily closed to hold the sheet in place, and which will be self-locking in the closed position so that it cannot be accidentally opened.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

20 Fig. 1 is a perspective view illustrating the improved arch lock binder in place on a backing board.

Fig. 2 is a front view of the improved binder.

25 Fig. 3 is a cross section therethrough, taken on the line 3—3, Fig. 2, illustrating the binder in the closed position.

Fig. 4 is a similar view illustrating the binder in the open position.

Fig. 5 is a plan view of the binder.

30 The invention is designed for attachment to any suitable supporting surface such as a backing board 10 for receiving a pile of superimposed sheets, such as indicated in broken line at 11.

The binder employs a plate 12 provided with a hanging opening 13 adjacent its upper edge. Two angle brackets 14 project from the face of the plate 12 in opposed relation.

40 A shaft 15 is pivotally supported between the angle brackets 14. A series of curved arch members 16 are mounted on the shaft 15 and supported in parallel, concentric relation thereon. Any number of the arch members may be employed. In the standard model there are two such members, as illustrated.

45 Each of the arch members is supported in its concentric position by means of an integral, radial arm 17 formed thereon and extending into the shaft 15. The arms 17 join, at their one extremity, the arch members 16 in relatively short radius bends 18. The free extremities of the arch members are pointed, as shown at 19, and enter receiving sockets 20 in sheet supporting posts 21 fixedly projecting from the plate 12.

50 The arch members may be swung from their open and closed positions by means of a crank

shaft 22 pivotally supported between the angle brackets 14. The crank shaft terminates to one side of the plate 12 in a finger hold 23. Between the bracket members, the shaft is offset to form a crank portion 24. The crank portion of the 5 crank shaft is held against the arms 17 by means of a hooked retaining member 25. The hooked extremity of the retaining member 25 extends beyond the small radius bend 18 of the arch members, as shown in Fig. 3. 10

To open the arch members, the crank shaft is rotated so that the crank portion 24 thereof will move downwardly. In moving downwardly, it presses against the retaining member 25, as shown in Fig. 4, to rotate the shaft 15 and swing 15 the arch members open.

To close the arch members, the crank shaft is rotated in the opposite direction to swing the crank portion 24 thereof upwardly. In moving upwardly, the crank portion acts against the arms 20 17 to force the arch members 16 to their closed position in their sockets 20. When the closed position is reached, the crank portion 24 is in the solid line position of Fig. 3, just below the bends 18. The further rotation of the crank 25 shaft snaps the crank portion thereof over these bends to a point above them, as shown in broken line in Fig. 3, so that it will be tangentially in line with the opening pressure of the arch members. Any attempt to pull these members open 30 will simply cause them to push against the crank portion 24 without rotating the latter. The device is therefor locked closed.

To release the lock, it is only necessary to rotate the shaft 22 counterclockwise as viewed in 35 Fig. 3 until it snaps over the bends 18 to the solid line position of Fig. 3. Further movement will open the arch members.

40 While a specific form of the improvement has been described and illustrated herein, it is desired to be understood that the same may be varied, within the scope of the appended claims, without departing from the spirit of the invention.

Having thus described the invention, what is 45 claimed and desired secured by Letters Patent is:

1. An arch lock binder comprising: a plate member; bracket members extending from said plate member; a shaft rotatably supported between said bracket members; arch members secured on said shaft and extending thereabout terminating in free extremities; binding posts positioned to receive the free extremities of the arch members when the latter are closed; a crank shaft supported between said bracket members; 50 55

and an offset portion on said crank shaft positioned to contact said arch members when said crank shaft is rotated for swinging the arch members to the closed position.

- 5 2. An arch lock binder comprising: a plate member; bracket members extending from said plate member; a shaft rotatably supported between said bracket members; arms extending radially outward from said shaft; arcuate arch members joined to said arms at their one extremities and extending in planes at right angles to said shaft; binding posts carried by said plate for receiving the free extremities of said arch members; and a rotatable crank shaft supported between said bracket members and contacting said arms to swing said arch members to the closed position.
- 10 3. An arch lock binder comprising: a plate member; bracket members extending from said plate member; a shaft rotatably supported between said bracket members; arms extending radially outward from said shaft; arcuate arch members joined to said arms at their one extremities and extending about said shaft; binding posts carried by said plate for receiving the free extremities of said arch members; a rotatable crank shaft supported between said bracket members and contacting said arms to swing said arch members to the closed position; and a retaining member extending from said shaft parallel to said arms and riding against the opposite side of said crank shaft so that reverse rotation of the latter will open said arch members.
- 15 4. An arch lock binder comprising: a plate member; bracket members extending from said plate member; a shaft rotatably supported between said bracket members; arms extending radially outward from said shaft; arcuate arch members joined to said arms at their one extremities by short radius bends and extending circumferentially about said shaft; binding posts carried by said plate for receiving the free extremities of said arch members; a rotatable crank shaft supported between said bracket members and contacting said arms to swing said arch members to the closed position; a retaining member extending from said shaft parallel to said arms and riding against the opposite side of said crank shaft so that reverse rotation of the latter will open said arch members; and a hooked extremity on said retaining member for limiting the closing movement of said crank shaft, said hooked extremity being so positioned that said crank shaft can travel past the short radius bends after the arch members have reached their closed position.

members joined to said arms at their one extremities; binding posts carried by said plate for receiving the free extremities of said arch members; a rotatable crank shaft supported between said bracket members and contacting said arms to swing said arch members to the closed position; a retaining member extending from said shaft parallel to said arms and riding against the opposite side of said crank shaft so that reverse rotation of the latter will open said arch members; and a hooked extremity on said retaining member for limiting the closing movement of said crank shaft.
